FLUID DISPLACEMENT APPARATUS

Myren W. Dole, Belmont, Mass.

Application May 2, 1935, Serial No. 19,454

Renewed March 24, 1937

10 Claims. (Cl. 122—434)

This invention relates to an apparatus for causing the displacement, or movement of a fluid, against resistance to the displacement of said fluid which may be encountered, due to gravity, 5 opposing pressure, pipe friction, or other cause; by the direct action of vapor pressure upon the fluid which is to be displaced, said apparatus being arranged to continue to operate as long as the vapor pressure acts upon the fluid. By "vapor pressure" I wish to be understood as referring to any gaseous material which may be under pressure, such as steam, air, carbon dioxide, etc.

Such an apparatus is useful for various purposes, such as displacing fluids where the vapor pressure is insufficient to operate a pump, ejector, or other similar device, or where the use of such pump, ejector, or other similar device is inexpedient for any one of various reasons.

One very important use for this fluid displacement apparatus is to supply water to the feed water heating and storage compartments of a locomotive feed water heater, of the type illustrated in my pending application (Serial No. 7,187), to which reference is herewith made.

One of the objects of my present invention is to provide a simple, inexpensive and positive device for raising, or displacing, a fluid against pressure, or other resistance which may oppose said displacement.

Another object is to provide a device which shall operate on a small vapor pressure, such for example as the pressure of steam exhausted from the cylinders of a steam engine.

Another object of my present invention is to provide a device which shall displace a fluid which may be so hot that the ordinary type of fluid pump, or ejector will fail to function.

Still another object of my present invention, when used with my previously mentioned locomotive feed water heater, is to provide an apparatus which shall automatically maintain substantially a pre-determined water level in the feed water heating compartment and which shall rapidly supply a large quantity of water to this and to the storage compartments and thus quickly restore the water level when the latter falls below the pre-determined point.

A still further object of my present invention is to provide an apparatus which when applied to my previously mentioned feed water heater shall operate on the exhaust steam which is brought to the tender primarily for heating the feed water, and shall operate even when the locomotive is working light and thus the exhaust pressure is small. This feature obviates the

necessity of bringing live steam from the locomotive to the tender, as would be the case if a pump were used, or of requiring a high exhaust steam pressure to maintain the water level in the heating and storage compartments, as would be 5 the case of an ejector were used for this purpose.

A still further object of my present invention, when applied to the aforementioned locomotive feed water heater, is to utilize the surging of the water, due to the motion of the tender, to obtain a water level as much above that in the supplying compartment as possible, in all of the compartments receiving their water from the supplying compartment by gravitational flow.

Further objects are to otherwise improve my aforementioned feed water heater, as will be more fully hereinafter set forth and pointed out in the appended claims.

In order to give an understanding of the invention I have illustrated in the drawings a 20 selected embodiment thereof, which in this case is my present invention as it might be applied to a locomotive feed water heater, such as the one to which I have previously referred, in my pending application (Serial No. 7,187), which will now 25 be described, although it will be understood that numerous and varied changes in the design of the apparatus may be made without in any way departing from the intent of my invention, likewise its application is to be understood as not 30 limited to a locomotive feed water heater.

In the drawings:

Fig. 1 is a sectional view showing a locomotive tender arranged substantially as set forth in my aforementioned pending application, for feed 35 water heating, but modified as required for the use of the improvements contained in my present invention. This section is taken on the line 1, 1.

Fig. 2 is a plan view of the tender with a portion shown as a section on the line 2, 2 and 40 40 with a portion broken out in order to disclose further details.

Fig. 3 is a fragmentary and enlarged section on the same line 1, 1 as was Fig. 1, having the details which were clearly shown in Fig. 1 45 removed, in order to disclose more clearly certain new features which will be described hereafter.

In the drawings, 1 indicates a portion of a locomotive and 2 the tender thereof. As is usual with 50 tenders of this particular type, this tender is provided with the transverse horizontal partition 3 which forms the floor of the coal compartment 4, the front end 5 of which floor constitutes the usual shoveling plate.

The space beneath the partition 3 constitutes the space for the storage of water, and this space is divided by partitions into a plurality of compartments, one of which is a main water compartment 5 and another of which is a feed water heating compartment. In the construction herein illustrated there are four such partitions 6, 7, 8, and 9 which divide the water space of the tender into the main water compartment 10, the feed water heating compartment 11, an auxiliary or storage compartment 12, an intermediate compartment 13, and a pressure chamber 14, although in some cases the use of more than one pressure chamber might be desirable and would not depart from the invention. The number of storage or other compartments between the main compartment 10 and the feed water heating compartment 11 may be varied also, without departing from the invention. The compartments 11, 12, and 13 extend underneath the floor of the coal compartment and in the construction shown they also extend along one side of said coal compartment to a point somewhat above the floor 3, and for this purpose the tender is made with the vertical wall 15 forming the inner wall of the upper portion of these compartments and with the plate 16 forming the top of said compartments.

The compartments and pressure chamber have communication at their lower portions through ports which permit gravitational flow from the main water compartment 10 to the intermediate compartment 13 and from thence to pressure chamber 14, and also from intermediate compartment 13 to the storage compartment 12 and thence to heating compartment 11. The port in partition 8 is controlled by a flap or non-return valve 17, the approach to this port being through the flaring funnel, or scoop, 18, the object of this funnel being to cause as much water as possible from compartment 10 to enter the port, due to the surging of the water in the tender.

Flap valve 19 controls the port leading into pressure chamber 14, while flap valves 20 and 21 control the ports giving access to the storage and heating compartments respectively.

The feed water heating compartment 11 and the storage compartment 12 both have communication at their upper parts with the cold water compartment 10 by means of the restricted vents 22 and 23 and the vent pipe 24, which latter is of ample size.

An exhaust steam supply pipe is indicated by 25 and this pipe is adapted to receive exhaust steam from the locomotive cylinders and deliver it to the feed water heating compartment 11. This cylinder exhaust may be delivered to the feed water in the heating compartment 11 by means of the spray pipe 26, or other suitable heat exchanger, may be diverted by control 27 into storage compartment 12 and delivered to the water therein by spray pipe 28, or other suitable heat exchanger, may be shut off from storage compartment 12 by control 29, whose upper end is closed by closure plate 30, or may be re-directed back to the water in heating compartment 11, by the action of control 27; all as set forth in my previously referred to pending application (Serial No. 7,187).

Another exhaust steam supply pipe 31 is indicated and this pipe is adapted to receive the exhaust steam from the locomotive auxiliary devices, such as head light generator, air pump, feed pump, stoker engine, booster engine, etc. This exhaust steam may be delivered to the water in heating compartment 11 by means of spray

pipe 32, or other suitable heat exchanger, may be diverted by control 33 into storage compartment 12 and delivered to the water therein by spray pipe 34, or other suitable heat exchanger.

Again it is possible, if there is sufficient pressure in compartments 11 and 12, to have control 35 divert this exhaust steam from the locomotive auxiliary devices previously enumerated, into the water contained in intermediate compartment 13 by means of spray pipe 36, or other suitable heat exchanger, thus heating the water therein contained, the latter being the feed water for the pressure chamber 14, and at the same time providing that at all times there shall be an open exhaust for the auxiliaries, in order that they may continue to run, which would not be the case if one of the controls were permitted to close off pipe 31, as was the case with pipe 25.

Another possibility, as to the disposal of the exhaust steam from the auxiliaries, is that control 33 may re-divert the steam back into feed water heating compartment 11, due to the pressure being relieved therein by being dissipated at the vent or by condensation caused by the injection of cooler water, as will be discussed later on. All of these possible disposals of the exhaust steam from the locomotive auxiliaries are substantially as set forth in greater detail in my previously referred to pending application (Serial No. 7,187).

Since in the operation of the heater there is likely to be developed in compartments 11 and 12 sufficient pressure to interfere with the gravitational flow of water into said compartments, and thus, since it is highly desirable that both of said compartments shall be maintained substantially full of water at all times, I have provided herewith novel means for maintaining a practically constant water level in said feed water heating compartment 11 and in storage compartment 12, independently of the gravitational flow of water to these compartments.

For this purpose I propose to employ one or more pressure chambers, through a port in the lower part of which water shall enter by gravitational flow, but which water is prevented from leaving through the entrance port by a flap or non-return valve. Pressure may be admitted to the upper part of the aforementioned pressure chamber, or pressure chambers, and a delivery pipe is provided for conducting the water contained in the pressure chamber to storage compartment 12 and to heating compartment 11.

In order that the operation of the device may continue as long as water is needed in the above mentioned compartments, I propose to use a valved means for cutting off the pressure from the pressure chamber, when the latter is emptied, and at the same time to vent the pressure which is already therein, in order to permit gravitational ingress of more water and thus the repetition of these operations until the water level in compartments 11 and 12 is restored.

In my selected embodiment of means for accomplishing the above results, I have provided pressure chamber 14, the port giving ingress to the lower part of which is controlled by the flap valve 19. I have shown this pressure chamber as receiving its water from the intermediate compartment 13, in order to take advantage of whatever heating of the water therein may have been accomplished by the spray pipe 36. A pipe connection 37 brings exhaust steam from pipe 25, which steam passes through valve 38, said valve being controlled by float 39, valve 38 being so arranged and located that when the water

level in feed water heating compartment 11 is at the predetermined point the float 39 is raised and valve 38 is closed, thus allowing no steam to flow in pipe 37. When however the water 5 level in feed water heating compartment 11 drops appreciably from the predetermined point, the float 39 is lowered and valve 38 permits steam to flow through pipe 37.

In pressure chamber 14, pipe 37 contains another valve 40, controlled by float 41, and so arranged and located that when float 41 is raised by water in the pressure chamber the valve 40 is opened and allows steam to flow through pipe 37 and to the upper part of pressure chamber 14. 15 When pressure chamber 14 is emptied however, float 41 is lowered and valve 40 being thus closed, stops the flow of steam through pipe 37 and to the upper part of pressure chamber 14. At the 20 top of chamber 14 is a restricted vent 42, through which pressure may escape to intermediate compartment 13 and thence through vent pipe 24 to the upper part of the main compartment 10, so that the pressure in chamber 14 may be relieved thereby.

25 A pipe 43, of generous size, extends nearly to the bottom of pressure chamber 14 and leads into storage compartment 12 where a small part of the flow in pipe 43 is conducted therefrom by pipe 44 and is added to the water in compartment 12. The major portion of the flow in pipe 43 is conducted to the feed water heating compartment 11 where it is discharged in the upper part of said compartment through a spray nozzle, or spray valve 45. Thus most of the water 30 flowing through pipe 43 is discharged in the form of a spray, into the steam which is present in the upper part of feed water heating compartment 11 much of the time. Discharging this water as a spray, tends to heat the water before it joins that 35 already in compartment 11, aids in the occlusion of air and gases from the water, and by condensing the steam which is in the upper part of compartment 11, reduces the pressure therein and thus causes a rapid action of controls 27 and 40 43 to divert all of the exhaust steam back into compartment 11 where it is needed, since water which may be cold, or cool, is now being injected 45 therein through spray nozzle 45.

The operation of the entire fluid displacement apparatus is as follows. When water is 40 removed from the feed water heating compartment 11, by the feed pump, or other boiler feeding device, through suction outlet 46, the dropping of the water level in the compartment lowers float 39, opens valve 38 and allows exhaust steam to flow in pipe 37. The water in pressure 45 chamber 14, being at the level of that in intermediate compartment 13, has raised float 41, opened valve 40 and thus allows steam flowing 50 in pipe 37 to reach the top of pressure chamber 14. This pressure acting upon the surface of the water contained in pressure chamber 14 displaces the water and forces it upward through water delivery pipe 43. It might be noted in passing 55 that this displacement of water takes place regardless of the temperature of the water, which if hot might cause difficulty if a pump or ejector were used. A part of the flow of water in delivery plate 43 passes into storage compartment 12 60 through the restricted pipe 44, but as has already been stated, the major portion of the flow in pipe 43 passes into the feed water heating compartment 11, through spray nozzle 45.

When the water in pressure chamber 14 has 65 passed upward through water delivery pipe 43,

if the amount has not been sufficient to raise the water level in feed water heating compartment 11 to the predetermined point and thus raised float 39, closed valve 38 and stopped the flow of steam in pipe 37, it is obvious that pressure 5 chamber 14 must be again filled with water and the process repeated. With the pressure which now fills pressure chamber 14, holding flap valve 19 to its seat, it is clear that no water will enter 10 the pressure chamber.

To take care of this situation, my invention provides valve 40 controlled by float 41 and the restricted vent 42. As soon therefore as the water is removed from pressure chamber 14, float 41 is lowered, valve 40 is closed and the flow of steam in pipe 37 is stopped. The pressure which is already in pressure chamber 14 is soon dissipated by the restricted vent 42 and this allows the water contained in intermediate compartment 13 to enter pressure chamber through flap valve 19 and thus fill the pressure chamber to the level of the water in the intermediate compartment. Water thus again flowing into the pressure chamber 14, raises float 41 and opens valve 40. Thus again admitting steam to the upper part of pressure chamber 14, provided only that float 39 is still lowered and valve 38 still open, causes the cycle of operations to be repeated and to continue until such time as the water level in feed water heating compartment 11 is raised to the predetermined point and the rising of float 39 closes valve 38 and stops the flow of steam to the pressure chamber 14 and thus stops the further action of the displacement apparatus.

35 I claim:—

1. A fluid displacement apparatus comprising a supply compartment containing the fluid to be displaced and having a variable fluid level therein, a receiving compartment, a vented pressure chamber communicating with the supply 40 compartment and receiving fluid therefrom by gravitational flow, means controlled by the fluid level in the receiving compartment to supply gaseous material under pressure to the pressure chamber when the fluid level in said receiving 45 compartment falls below a predetermined point, means providing such a communication between said pressure chamber and the receiving compartment that the fluid in the pressure chamber is forced into the receiving compartment when 50 pressure is developed in said pressure chamber by admission of gaseous material thereto and means controlled by the level of the fluid in the pressure chamber to shut off the supply of gaseous material thereto when the fluid level therein 55 falls below a predetermined point.

2. A fluid displacement apparatus comprising a supply compartment containing the fluid to be displaced and having a variable fluid level therein, a receiving compartment, a pressure chamber 60 communicating with the supply compartment and receiving fluid therefrom by gravitational flow through a port controlled by a non-return valve, means controlled by the fluid level in the receiving compartment to supply gaseous material under pressure to the pressure chamber, when the fluid level in said receiving compartment falls below a predetermined point and means providing such a communication between 65 said pressure chamber and the receiving compartment that the fluid in the pressure chamber is forced into the receiving compartment when pressure is developed in said pressure chamber by admission of gaseous material thereto and means controlled by the fluid level in the 70 pressure chamber to shut off the supply of gaseous material thereto when the fluid level therein falls below a predetermined point.

75

pressure chamber to shut off the supply of gaseous material thereto when the fluid therein falls below a predetermined point and means to relieve the pressure existing in said pressure chamber when the supply of gaseous material is shut off.

3. A feed water heater for locomotives comprising a tender having a main water compartment, a feed water heating compartment, a 10 vented pressure chamber, means providing for gravitational flow of water from the water compartment into the pressure chamber, a water delivery pipe leading from near the bottom of the pressure chamber to the feed water heating compartment, means responsive to a falling level 15 of water in the feed water heating compartment to supply steam under pressure in the pressure chamber thereby building up pressure therein which forces the water in said chamber through 20 the delivery pipe into the feed water heating compartment and means responsive to a falling level in said pressure chamber to shut off the supply of steam.

4: A feed water heater for locomotives comprising a tender having a main water compartment, a feed water heating compartment and a vented pressure chamber, means providing for gravitational flow of water from the main water compartment into the pressure chamber, a 30 water delivery pipe leading from near the bottom of the pressure chamber to the feed water heating compartment, means controlled by the water level in said feed water heating compartment to supply steam to the pressure chamber 35 when the water level in said feed water heating compartment falls below a predetermined point thereby building up a pressure in said pressure chamber which forces the water contained in the pressure chamber through the delivery pipe into the feed water heating compartment, means 40 controlled by the water level in the pressure chamber to shut off the steam supply to said pressure chamber when the water level in the latter falls below a predetermined point, and means 45 to heat the water in said feed water heating compartment.

5. A feed water heater for locomotives comprising a tender having a main water compartment, a feed water heating compartment and a 50 pressure chamber, means providing gravitational flow of water from the main water compartment into the pressure chamber, a water delivery pipe leading from near the bottom of the pressure chamber to the feed water heating compartment, means controlled by the water level in said feed water heating compartment to supply steam to the pressure chamber when the water level in 55 said feed water heating compartment falls below a predetermined point thereby building up a pressure in said pressure chamber which forces the water therein through the delivery pipe into the feed water heating compartment, means controlled by the water level in the pressure chamber to shut off the steam supply to said pressure chamber when the water level in the latter falls 60 below a predetermined point, means to relieve the pressure that exists in the pressure chamber when the steam supply is shut-off, and means to heat the water in the said feed water heating compartment.

6. A feed water heater for locomotives comprising a tender having a main water compartment, a feed water heating compartment, an auxiliary heating or storage compartment, and a pressure chamber; means providing for gravitational flow

of water from the main water compartment into the pressure chamber through a port controlled by a non-return valve; a water delivery pipe leading from near the bottom of the pressure chamber to the feed water heating compartment and 5 to the auxiliary heating, or storage compartment; means controlled by the water level in said feed water heating compartment to supply steam to the pressure chamber when the water level in said feed water heating compartment falls below 10 a predetermined point thereby building up a pressure in said pressure chamber which forces the water therein through the delivery pipe into the feed water heating and/or the auxiliary, or storage, compartment; means to heat the water in 15 said feed water heating and auxiliary, or storage, compartments; means controlled by the water level in the pressure chamber to shut off the steam supply thereto when the water level therein falls below a predetermined point and means to 20 relieve the pressure that exists therein after the steam supply is shut-off.

7. A feed water heater for locomotives comprising a tender having a main water compartment with a varying water level therein, a feed water heating compartment and a vented pressure chamber, means providing for gravitational flow of water from the main compartment into the pressure chamber, a water delivery pipe leading from near the bottom of the pressure chamber to the feed water heating compartment, means controlled jointly by the water level in the feed water heating compartment and in the pressure chamber to supply steam to the pressure chamber when the water level in the feed water heating compartment is below a predetermined point and the water level in the pressure chamber is above a predetermined point.

8. A feed water heater for locomotives comprising a tender having a main water compartment with a varying water level therein, a feed water heating compartment and a vented pressure chamber, means providing for gravitational flow of water from the main compartment into the pressure chamber, a water delivery pipe leading from near the bottom of the pressure chamber to the feed water heating compartment, means controlled jointly by the water level in the pressure chamber to supply steam to the pressure chamber when the water level in the feed water heating compartment is below a predetermined point and the water level in the pressure chamber is above a predetermined point and to shut off the supply of steam when the water level in the feed water heating compartment rises to another predetermined point.

9. A feed water heater for locomotives comprising a tender having a main water compartment with a varying water level therein, a feed water heating compartment and a vented pressure chamber, means providing for gravitational flow of water from the main compartment into the pressure chamber, a water delivery pipe leading from near the bottom of the pressure chamber to the feed water heating compartment, means controlled jointly by the water level in the feed water heating compartment and in the pressure chamber to supply steam to the pressure chamber when the water level in the feed water heating compartment is below a predetermined point and the water level in the pressure chamber is above a predetermined point and to shut off the supply of steam when the water level in 70

the pressure chamber falls to a predetermined point.

10. A feed water heater for locomotives comprising a main water compartment with a varying water level therein, a feed water heating compartment, a vented pressure chamber, means providing for gravitational flow of water from the main water compartment into the pressure chamber, a water delivery pipe leading from near the bottom of the pressure chamber to the feed water heating compartment, a steam supply pipe leading to the feed water heating compartment and two valves therein, one controlled by a float in the feed water heating compartment and the other by a float in the pressure chamber.

MYRON W. DOLE.
